BRIDLE BIT

Leland B. Bergen, Millbrae Highlands, Calif.

Application June 25, 1946, Serial No. 679,042

4 Claims. (Cl. 54—6)

1

This invention relates to a bridle bit intended for leading and driving horses, and particularly to improvements on the type of bit disclosed in my former patent, No. 2,012,705, entitled "Bridle bit," and issued August 27, 1935.

There are a considerable variety of bridle bits in use for leading and driving horses such as Mexican bits, curved bits, etc. Bits of this character are particularly intended for hard-bitted and more or less intractable horses, and while they serve the purpose of keeping the horse under control, they are usually too severe as there is a tendency to cut, bruise and pinch the corners of the mouth.

The bit shown in the above-mentioned patent is in extensive use and is known as the humane bit as it materially reduces the chance of cutting, bruising and pinching the horse's mouth. The present invention is an improvement thereon, and the object is to form a pivotal connection between the mouth and cheek pieces of the bit, and particularly to limit the pivotal movement of the cheek-pieces with relation to the mouth-piece, so as to further reduce any tendency to cut, bruise or pinch the horse's mouth.

The improved bridle bit is shown by way of illustration in the accompanying drawings, in which:

Fig. 1 is a front view of the bit partially in section;

Fig. 2 is a side elevation of the bit taken on line II—II of Fig. 1;

Fig. 3 is a horizontal section taken on line III—III of Fig. 1; and

Fig. 4 is a perspective view showing the bit applied to a horse.

Referring to the drawings in detail, and particularly Fig. 1, A—A indicates the cheek-pieces of the bit, B the mouth-piece and C the straps forming the head stall whereby the bit is held in place. The cheek-pieces are in this instance connected by two cross-bars generally indicated at B and D, the bar B forming the mouth-piece, and the bar D the hinge bar.

By referring to Figs. 1 and 2, it will be noted that the upper portion of each cheek-piece is formed in the shape of a ring such as indicated at 2. These rings are in actual practice an inch and a half or more in diameter and each ring is provided with a pair of diametrically opposed bearing lugs 3 and 4. These lugs are bent or extended outwardly as clearly shown in Fig. 1, and pins 5 extend between them and are secured thereto to form pivotal connections between the

2

cheek-pieces and the outer ends of the mouth-piece B, as clearly shown in Figs. 1 and 3.

The pivotal connections thus formed will accordingly be offset with relation to the inner faces 2a of the cheek-pieces and any tendency to cutting or pinching of the corners of the horse's mouth will accordingly be reduced.

The upper portions of the rings 2 forming the upper ends of the cheek-pieces are provided with 10 loop-like extensions 6 to which the head stall strap C is attached, a curb strap E being also attached at the same place. The cheek-pieces are extended downwardly from the rings 2—2 and these extensions may be in the shape shown in 15 my former patent, or in the form of a series of connected ring-shaped members 7 as here shown. Each lowermost ring-shaped member of the extended cheek-pieces carries a pivot pin 8. These pins carry the hinge bar D. The pins form pivotal 20 connections between the cheek-pieces and the hinge bar and as the pins 8 align with the pins 5 as shown in Fig. 1, free pivotal movement of the cheek-pieces with relation to the bars B and D is permitted. Inasmuch as the pins 5 are offset 25 with relation to the inner faces 2a of the cheek-pieces, it is obvious that they will have to be angularly disposed, and so will the pins 8. It is due to this offsetting of the pins 5 that both sets of pins must be angularly disposed with relation 30 to their respective cross-bars, and if free pivotal movement is to be permitted, the pins 5 and 8 must align. Such alignment is indicated by the dotted line 9—9 (see Fig. 1). The center portion of the hinge bar D carries an eye member 15 and 35 a chain 16 connects this eye member with the curb strap E. This chain may be referred to as the lip hold-down chain as it prevents the horse from lipping the bit, and it also prevents the horse from throwing the bit over his nose, and it 40 furthermore holds the bit steady when riding or driving.

The mouth-piece B may be provided with a port and a cricket or roller such as shown at 19, or a spoon type mouth-piece, or any other type 45 may be employed, the main feature being that the pivotal connection 5 between the cheek-pieces and the mouth-piece shall be offset so that when the bit piece is in the horse's mouth, the pivotal connection does not come in contact with the corners 50 of the mouth. This arrangement distributes pressure evenly and reduces any tendency towards cutting and pinching. The bit so far described is substantially the same as that disclosed in my patent, No. 2,012,705, formerly referred to. The 55 improvement in the present bit over the former bit

is that of providing means for limiting pivotal movement of the cheek-pieces with relation to the mouth-piece. By referring to Figs. 1 and 3, it will be noted that the pins 5 are each provided with an arm 25 and that these arms extend into recesses 26 formed adjacent each end of the mouth-piece. Each recess terminates in shoulders 27 and 28 at opposite ends, hence when the cheek-piece pivots or swings with relation to the mouth-piece, the free pivotal movement will be limited as the arm 25 will engage one or another of the shoulders. This is important as it further reduces any tendency toward cutting, bruising, or pinching the corners of the horse's mouth.

It is a fact that bits which pinch and cut the corners of the mouth spoil horses by causing them to throw their heads, to fight the bits, and it causes them to become hard-mouthed or cold-jawed. By limiting the possibility or necessity of such cruel biting by the use of the bit here illustrated, a horse is made tractable and easily reined, yet there is no weakness in the construction of the bit itself or in the control of the driver.

Besides the humane features provided by this improved bit, it lends itself to artistic and ornamental design, and while this and other features of the invention have been more or less specifically described and illustrated, it should be understood that changes may be resorted to within the scope of the appended claims and that the materials and finish of the several parts employed may be such as the experience or judgment of the manufacturer may dictate or varying conditions or uses may demand.

Having thus described my invention, what I claim and desire to secure by Letters Patent is:

1. A bridle bit comprising a pair of cheek-pieces, said cheek pieces being ring-shaped at their upper ends, a pair of diametrically opposed bearing lugs in each ring, a mouth-piece, pins extending through the bearing lugs and the outer ends of the mouth-piece to form pivotal connections between the cheek-pieces and the mouth-piece, said bearing lugs being bent outwardly with relation to the inner faces of the cheek-pieces so as to bring the pivotal connection in a plane exterior to said inner faces, and means disposed between said pivotal connections for limiting pivotal movement of the cheek-pieces with relation to the respective ends of the mouth-piece.

2. A bridle bit comprising a pair of cheek-pieces, a pair of diametrically opposed bearing lugs in each cheek-piece, a mouth-piece, pins extending through the bearing lugs and the outer ends of the mouth-piece to form pivotal connections between the cheek-pieces and the mouth-piece, an inwardly directed arm on each pin, there being a recess formed within each end of the mouth-piece into which the arms extend, and a pair of opposed shoulders in each recess with which the adjacent arm is engageable to limit pivotal movement of the cheek-pieces with relation to the mouth-piece.

3. A bridle bit comprising a pair of cheek-pieces, said cheek-pieces being ring-shaped at their upper ends, a pair of diametrically opposed bearing lugs in each ring, a mouth-piece, pins extending through the bearing lugs and the outer ends of the mouth-piece to form pivotal connections between the cheek-pieces and the mouth-piece, an inwardly extending arm on each pin, there being recesses formed between the bearing lugs adjacent each end of the mouth-piece into which the arms extend, a pair of opposed shoulders in each recess with which the arms are engageable to limit pivotal movement of the cheek-pieces with relation to the mouth-piece, said bearing lugs extending outwardly with relation to the inner faces of the cheek-pieces so as to bring the pivotal connection in a plane exterior to said inner faces, a downwardly extending portion on each cheek-piece, a lower hinge bar and a pivotal connection between the lower end of each cheek-piece and the hinge bar, said pivotal connections aligning with the pins about which the cheek-pieces pivot with relation to the mouth-piece.
4. A bridle bit comprising a pair of cheek-pieces each having an inner face and an outer face; a hinge bar; means pivoting said hinge bar to both of said cheek-pieces for rotation about axes each extending outside the outer face of a respective one of said cheek-pieces; a pair of opposed bearing lugs extending outwardly from each of said cheek-pieces; a mouth piece adjacent both ends thereof having facing walls defining enlarged recesses extending therethrough; a pair of pivot pins one being disposed on each of said axes, extending through an adjacent one of said recesses, and engaging the respective ones of said bearing lugs; and arms projecting from said pins inwardly of said axes and each being engageable with either of said adjacent facing walls to limit the movement of the respective cheek-pieces with respect to the respective one of said hinge bar and said mouth-piece about said axes.
